United States Patent

Des. 241,940
Patented Oct. 19, 1976

241,940

TURNSTILE

Hermann Eberhardt, 10 Schlesierstrasse,
D-7928 Giengen (Brenz), Germany

Filed Sept. 9, 1974, Ser. No. 504,656

Term of patent 14 years

Int. Cl. D25—02

U.S. Cl. D25—57

FIG. 1

FIG. 4

FIG. 5

FIG. 2

FIG. 3

FIG. 1 is a top view of a turnstile embodying my new design;

FIG. 2 is one perspective front view of the turnstile shown in FIG. 1;

FIG. 3 is a perspective side view of the turnstile shown in FIG. 1;

FIG. 4 is a front view of the turnstile shown in FIG. 1; and

FIG. 5 is a side view of the turnstile shown in FIG. 1. I claim:

The ornamental design design for a turnstile, substantially as shown and described.
